UNITED STATES PATENT OFFICE

JOHN F. HARRIS, OF STROUDSBURG, PENNSYLVANIA

SELECTIVELY-CONTROLLED DISTRIBUTING BOX FOR SEWAGE-DISPOSAL SYSTEMS

Application filed April 12, 1929. Serial No. 354,584.

This invention relates to a distributing box for sewage disposal systems and an object of the invention is to provide for selectively closing the outlet conductors from a distributing box and permitting other outlet conductors to discharge to permit the earth to carry away excess discharge from the area closed.

Further objects of the invention are to provide, in a manner as hereinafter set forth, a distributing box of the character referred to, which is strong, compact and durable, highly efficient for its intended purpose, and thoroughly reliable in its operation, which is very simple to manufacture and install, and promoting economy in disposing of sewage.

With the foregoing and other objects in view, the invention consists in the novel construction, combination and arrangement of parts as will be hereinafter more specifically described and illustrated in the accompanying drawings, wherein is disclosed an embodiment of the invention, but it is to be understood that changes, variations and modifications may be resorted to, without departing from the spirit of the claims hereunto appended.

In the drawings, wherein like reference characters denote corresponding parts throughout the several views:

Figure 1 is a side elevation of the device in accordance with this invention submerged below the level of the earth.

Figure 2 is a longitudinal section taken substantially on the line 2—2 of Figure 1, and

Figure 3 is a vertical section taken substantially on the line 3—3 of Figure 1.

The distributing box in accordance with this invention is particularly adapted to distributing waste waters from septic, sedimentation, settling tanks or other sewage disposal systems where the water from such systems is divided so as to distribute the egress thereof over a greater area of the earth's surface.

Referring to the drawings in detail, wherein is disclosed an embodiment of the invention, 5 indicates a hollow, closed segmental shaped reservoir having an arcuate side 6

and the chorded side 7 secured at their points of merger and top and bottom segmental shaped walls 8, 9. All of the walls are provided with steel reinforcing members 10 so as to provide a stronger and better concrete 55 wall. The inner faces of the top and bottom walls 8 and 9 are formed with right angled inset grooves 11, 12, coextensive with the outer perimeter thereof. The upper and lower edges of the side walls 6 and 7 are butted with cement and coupled to top and bottom walls by seating in the angular grooves 11, 12.

An inlet conductor 13 extends through the arcuate side wall 6, at a point equi-distant 65 from the ends thereof and slightly below the horizontal center of the wall. A plurality of longitudinally spaced outlet conductors are secured to and extend through the chorded wall 7 at a lower lever than the inlet conductor 13. The area of the outlet conductors 14 are substantially the same as the inlet conductors 13 and are spaced from each other a greater distance than the diameters thereof. The inner end of the outlet conductors 70 14 projects slightly beyond the inner face of the wall 7 so as to provide for seating the valve to be presently described. The reservoir 5 is to be submerged below the surface of the earth 15, and communicating therewith 75 from the surface is a soil pipe, 16, the lower end of which is anchored in the top wall 8. The upper end of the soil pipe 16 is provided with a screw cap, 17, which is flush with the surface of the ground and may be removable 80 for purposes referred to. A pair of bronze bushings 18, 19, are secured in the top wall 8 and the bottom wall 9 respectively in alignment with each other. Through the openings in the bushings is journalled a valve stem 85 20, on which is rigidly mounted a rectangular plate 21. The plate 21 is of such length and width that it will control adjacent pairs of outlet conductor pipes 14 at one side.

The upper end of the valve stem projects 90 beyond the top wall 8 of the reservoir and is provided with a square head 22, which terminates within the soil pipe 16. By removing the cap 17 and inserting the socket 95 on the lower end of the operating handle 23 100

on the head 22, the plate 21 may be rotated by the valve stem 20, whereby adjacent pairs of outlet conductors may be prevented from discharging. The plate 21 acts in all respects similarly to the ordinary flat valve and controls selectively the discharge through the outlet pipes as desired.

In the application of the distributing box in accordance with this invention, the same is particularly adapted to soils that absorb water slowly and when the area about any pair of the outlet conductors 14 becomes water clogged, the flat valve 21 may be closed cutting off the discharge through that pair, and permitting the flow to continue through the other pair of outlet conductors 14.

Having described my invention, what is claimed as new is:

1. A distributor box for sewage disposal systems comprising a hollow closed segmental shaped reservoir adapted to be placed below the surface of the earth, an inlet conductor pipe secured to and entering through the arcuate side of the reservoir, and a plurality of longitudinally spaced outlet conductor pipes secured through and extending laterally from the chord side of said reservoir, and means operable from the surface of the ground for selectively closing the adjacent pairs of outlets and permitting the remaining outlets to discharge.

2. A distributor box for sewage disposal systems comprising a hollow closed segmental shaped reservoir adapted to be placed below the surface of the earth, an inlet conductor pipe secured to and entering through the arcuate side of the reservoir, and a plurality of longitudinally spaced outlet conductor pipes secured to and extending laterally from the chord side of said reservoir, and means operable from the surface of the ground for selectively closing the adjacent pairs of outlets and permitting the remaining outlets to be discharged, said outlets being disposed at lower levels than said inlet conductors.

3. A distributor box for sewage disposal systems comprising a hollow closed segmental shaped reservoir adapted to be placed below the surface of the earth, an inlet conductor pipe secured to and entering through the arcuate side of the reservoir, and a plurality of longitudinally spaced outlet conductor pipes secured to and extending laterally from the chord side of said reservoir, and means operable from the surface of the ground for selectively closing the adjacent pairs of outlets and permitting the remaining outlets to be discharged, said outlets being disposed at lower levels than said inlet conductors, said means comprising a flat valve journaled in the top and bottom walls.

4. A distributor box for sewage disposal systems comprising a hollow closed reservoir adapted to be placed below the surface of the earth, said reservoir being of segmental shape

including an arcuate and a chord side, an inlet conductor pipe secured to and entering through the arcuate side of the reservoir, a plurality of longitudinally spaced outlet conductor pipes secured through and extending laterally from the chord side of the reservoir, and means operable from the surface of the ground for selectively closing the adjacent pairs of outlets and permitting the remaining outlets to discharge.

In testimony whereof I affix my signature.

JOHN F. HARRIS.
